AILERON

Edward F. Zaparka, Baltimore, Md., assignor to
 Zap Development Corporation, Baltimore, Md.,
 a corporation of Delaware

Application July 21, 1933, Serial No. 681,642

37 Claims. (Cl. 244—29)

This invention relates to airplanes, and more particularly to means for effecting lateral control of airplanes.

This application contains subject matter and 5 claims common to applicant's co-pending application Serial No. 653,918.

An object of my invention is to provide means for lateral control, such as aileron constructions which are simple in operation and will give a 10 very sensitive and powerful lateral control of the plane.

Another object of my invention is to provide such a construction in which the construction is sturdy, and in which there are few operating 15 parts and the repair and replacement are easily and cheaply effected.

With these and other objects in view, which may be incident to my improvements, the invention consists in the parts and combinations to 20 be hereinafter set forth and claimed, with the understanding that the several necessary elements comprising my invention may be varied in construction, proportions and arrangement, without departing from the spirit and scope of 25 the appended claims.

In order to make my invention more clearly understood, I have shown in the accompanying drawings means for carrying the same into practical effect without limiting the improvements in their useful applications to the particular constructions, which, for the purpose of explanation, have been made the subject of illustration.

In the drawings:

35 Figure 1 is a perspective view, part of the construction being broken away, showing an embodiment of my invention and the control means for effecting the positioning of the ailerons;

Fig. 2 is a diagrammatic top plan view of the 40 operating mechanism, parts of the mechanism being broken away to save space;

Fig. 3 is a cross sectional view taken through a wing showing one location of an aileron embodying my invention;

45 Fig. 4 is a cross sectional view taken through a wing showing another embodiment of my aileron;

Fig. 5 is a view similar to that shown in Fig. 50 4, showing a still further embodiment of my aileron;

Fig. 6 is a view similar to that shown in Fig. 4, showing yet another embodiment of my aileron;

55 Fig. 7 is a view similar to that shown in Fig.

4, showing still another embodiment of my aileron;

Fig. 8 is a perspective view of the detailed construction of the aileron itself, part of the cover of the aileron being removed to more clearly indicate the position of the parts; 60

Fig. 9 is a detail perspective view showing operating mechanism for a floating aileron construction;

Fig. 10 is a detail side elevational view of a 65 wing with a floating aileron construction;

Fig. 11 is a view similar to Figure 10, showing another floating aileron location;

Fig. 12 is a view similar to Figure 10, showing 70 another floating aileron location;

Fig. 13 is yet another view similar to Figure 10, showing still another floating aileron location;

Fig. 14 is yet another view similar to Figure 10 showing a different floating aileron location. 75

Referring to the drawings, in Fig. 1 I have shown an airplane having wings 1, a fuselage 2, a motor 3 provided with a propeller 4, and an empennage structure comprising a rudder 5, stabilizer surfaces 6 and elevators 7. 80

The wings 1 are provided with ailerons 8 mounted on aileron supports 9, as seen in Figure 3. The ailerons 8 are provided with horns 11. The mounting of the aileron and its interior construction are plainly apparent from an inspection of the view shown in Figure 8. Each aileron 8 consists of a longitudinally positioned torque tube 12 over which are mounted transverse bracing members 13 so shaped as to give the aileron, when covered by a suitable fabric 85 or other covering, the proper shape.

The transverse bracing elements 13 are joined to a rod 14 at their trailing edge and to another rod 15 at their leading edge. The transverse bracing members 13, located at the ends of the ailerons, are reinforced with a reinforcing structure 16. The torque tube 12 has attached to it the horn 11 above mentioned, which is provided with a ball 17 at its end adapted to cooperate with a socket joint located at 18 in control rods 19, for operating the ailerons. Attached to the longitudinally disposed torque tubes 12 are spaced supports 21 in which is journaled a pivot 22 carried by the aileron support 9. The position of the parts can be seen in dotted lines in Figure 3. 100

Each operating rod 19 for each aileron is provided with a socket joint 23 at its end which engages with a ball member 24 mounted on an operating arm 25. The operating arm 25 is preferably integrally formed with force transmitting 105 110

arms 26 and 27. To the force transmitting arm 26 is attached a cable 28, and to the force transmitting arm 27 is attached a cable 29. The member comprising the operating arm 25 and the force transmitting arms 26 and 27 is pivotally mounted at 31 on a bracket 32 attached to a forward wing spar 33.

The horn 11 is so positioned that for any given movement of the operating rod 19 there is a greater movement of the trailing edge of the aileron in the up or raised position than there is for the trailing edge of the corresponding opposite aileron into the down or lowered position. This type of movement is well known in the art and is not a novel feature with the applicant.

The cable 28 connects the force transmitting arms 26 and the cable 29 connects the force transmitting arms 27. The cable 29 passes over pulleys 34 and 35, and over other pulleys, not shown, located near the floor of the cockpit, and thence the cable 29 passes over a drum 36 which is adapted to be rotated by a hand wheel 37.

By rotating the hand wheel 37 through the cables 29 and 28, the operating arms 25 can be moved as indicated in dotted lines in Figure 2 to cause the ailerons 8 to assume the desired positions. When the aileron on the right hand wing is moved into the down position, (with its trailing edge lowered) the aileron on the left hand wing is adapted to be moved in the up position, (with its trailing edge raised) and as before stated, the movement of the trailing edge of the aileron into the up position will be greater than the movement of the trailing edge of the opposite aileron into the down position.

It will be noted that the ailerons 8 are narrow but long and, therefore, affect the flow of air over a substantial portion of the area of the upper surface of the wings. When an aileron is moved into the down position, at favorable angular setting, it affects the flow around the wing to tend to prevent burbling or turbulence, and tends to hold the flow in contact with the upper surface of the wing. This has a noticeable effect in increasing the lift coefficient of the wing on which the aileron is moved in the down position. By being moved into the down position, I mean that the trailing edge of the aileron is moved down. The lift coefficient, therefore, is increased and we have not only the effect of the aileron itself acting by its airfoil section in the flow to raise that wing when it is moved in its down position, but we have the additional effect of the aileron on the wing itself, tending to increase the efficiency of the wing as a lifting surface. This feature is of extreme importance and gives a sensitivity and positiveness of control which is highly desirable.

The effect is opposite upon the raising of an aileron, that is to say raising the trailing edge of the aileron tends to disturb the flow around the wing, thus tending to lower the lift coefficient of the wing upon which the aileron is raised.

The ailerons thus give both positive and negative lift effect on the wings themselves, which is in addition to the positive and negative lift effect which is achieved through the instrumentality of the ailerons acting by their airfoil sections in the flow.

Because of this unique effect of the aileron by reason of its location and form, efficiency and sensitivity of lateral control is greatly increased over prior practice.

In Figure 3 I have shown the aileron located

so that its pivot point is approximately half an aileron chord distant from the upper surface of the wing, and so positioned laterally with respect to the trailing edge that the nose of the aileron lies approximately about a half chord forward of the trailing edge of the wing. This location of the aileron is very efficient. There is a noticeable effect on the flow around the wing when the aileron is moved because the aileron is not too close to interfere with this desirable action.

In Figure 4 I have shown the aileron positioned laterally approximately the same as in the form of aileron shown in Figure 3, but the aileron is moved farther above the wing. In this instance the point of pivoting for the aileron is approximately a full aileron chord above the upper surface of the trailing edge of the wing.

In another form of my invention, such as in Figure 5, I have shown the aileron positioned laterally approximately as shown in Figures 3 and 4, but the pivot point of the aileron is moved approximately two aileron chords above the upper surface of the trailing edge of the wing.

In Figure 6 I have shown the aileron pivoted approximately half an aileron chord above the upper surface of the wing while the nose of the aileron is approximately two aileron chords forward of the trailing edge of the wing.

In Figure 7 I have shown the aileron pivoted approximately half a chord above the trailing edge of the wing but so mounted that the nose of the aileron is approximately a full aileron chord to the rear of the trailing edge of the wing.

The forms shown are the preferable forms of my invention. Preferably I locate the aileron from one third of a chord to two aileron chords above the trailing edge of the wing, and in such positions that the nose of the aileron shall be from two aileron chords in front of the trailing edge to one aileron chord in rear of the trailing edge of the wing. Another way of stating it is that the trailing edge of the aileron shall be approximately one chord in front of the trailing edge of the wing or two chords to the rear of the trailing edge of the wing. I do not desire to be limited within the exact limits as indicated. In some forms of construction the limits I propose may be used, or in some cases even increased, and in other forms of plane construction it is not desirable to have the aileron assume the positions indicated by the limits mentioned. In general it is desirable to so locate the ailerons above the wings as to increase the flow of the combination of aileron and wing on the side to be raised and to decrease the velocity of air flow over the upper surface of the opposite side. This produces a desirable rotation about the fore and aft axis of the plane, which is the product of the action of the ailerons themselves and of the effect of the air flow over the surfaces of the wings as modified by the aileron action.

While I have shown various positions of my aileron construction in the drawings and given some definite limits for efficiency of operation with respect to the position of the ailerons, I wish it to be distinctly understood that I am not limited in my broadest concept to the particular showings made. I believe myself to be the first to discover and put to practical application the use of ailerons which are distinct and separate from the major airfoil sections and which are not a part of the major airfoil section in any sense, and which affect the flow around a material por-

tion of the major airfoil section in addition to the reaction on the aileron itself due to its own airfoil section being changed through certain angular limits. Therefore, I do not wish to be limited to the particular showings made.

My researches have shown that other positions of ailerons than those indicated by the limits stated in this application possess to a certain degree the efficiency characteristics of the defined aileron. It is to be distinctly borne in mind that, basically, I believe myself to be the first to discover that an aileron which is in no sense a part of the major airfoil can be used to affect the flow around the major airfoil both positively and negatively to cause a sufficient change of the flow over a sufficient area of the main airfoil to produce a practical and usable rolling moment which is, in addition, to the rolling moments produced by the airfoil sections of the ailerons per se.

Therefore, the apparent indecision on aileron location is not one in effect and the phraseology of the above location definition is caused by the manner of stating the location point by multiples of aileron chord. There is, however, an interrelation existing as to favorable aileron location as to wing chord and aileron chord dimensions, and the location definitions given here are also taking care of that phenomenon. While we also term the location as specified by description of Figure 3 as a favorable one, the other locations are giving satisfactory results. The research which I have done is not limited to the positions of aileron illustrated, and other aileron positions around the main airfoil, such as in the vicinity of the forward part of the main airfoil, have proven advantageous and to possess the inherent operative features which I have here disclosed.

In order to explain what I mean by the term "downflow", as used in the claims, it must be remarked that the region of flow above a wing can be divided into two parts, namely, the upflow and the downflow, relative to the flight path of the airplane. The term "downflow" used in the claims refers to that region above the surface of the airfoil in which the airflow is deflected downward from its original relative direction parallel to the line of flight of the aircraft or wing.

It is the location of the ailerons substantially within the downflow over a wing which is of great importance in achieving the desirable reactions which I have described. In some instances the aileron may be located well forward of the forward position defined in aileron chords which I have just set forth, but so long as the aileron lies substantially within the downflow, the desirable results are obtained.

The term "downflow" as used in the claims also is intended to cover that flow of air which occurs back of and adjacent to the trailing edge of the wing. The word "downflow" therefore is intended to cover the flow of air around an aileron located above the wing but substantially rear of the trailing edge. Such airflow back of the trailing edge of the wing is often called "downwash", but the word "downflow" as I here employ it covers this downwash area as well as the flow of air adjacent to and over the upper rear surface of the wing.

Referring to the drawings, I have shown a floating aileron mechanism which is probably best shown in the perspective view, Figure 9. The location of these floating ailerons in my invention is the same as for the ordinary ailerons. There are certain inherent advantages in floating ailerons which are additional to the advantages of my

ordinary aileron construction. The type of floating aileron construction I have shown is one in which the ailerons float together. I have found that this type of floating aileron construction in the location which I employ is somewhat preferable to a floating aileron construction in which each of the ailerons may float separately. Where the ailerons float together there is more inherent stability in the combination than is the case where each aileron may separately float.

The floating ailerons I have designated by the numerals 50. These ailerons are pivoted at 51 on aileron horns 52 located on the upper surface of the wings 1. The ailerons are provided with horns 53 to which are pivoted at 54 aileron operating rods 55.

The aileron operating rods 55 are pivoted at 56 to crank arms 57 which are attached to shafts 58. The shafts 58 are suitably journaled on supports 59 attached to the front wing spars. The ends of the shafts 58 opposite the cranks 57 are provided with cranks 61 which carry ball members 62. The ball members 62 engage with socket members formed in enlarged portions 63 of rods 64.

The rods 64 at their lower ends carry socket members at 65 in which are adapted to pivot ball members 66 which are carried on operating arms 67. The arms 67 may be integrally formed and are attached to a shaft 68. An elongated link member 69 which is supported, as indicated at 71, at some suitable place in the fuselage, permits certain side play to the shaft 58 and a large up and down movement of the shaft 68. The side play, however, is not great.

The shaft 68 is coupled to a shaft 72 through a gimbal joint connection 73 which allows motion in all planes. The shaft 72 is journaled in supports 74 which are supported at some convenient place near the floor of the fuselage.

The control stick 75 is pivoted at 76 to the shaft 72. The control stick 75 is provided at its lower end with a U-shaped support member 77 through which the pivot 76 passes. The pivot 76 passes through an aperture in the shaft 72. The U-shaped support 77 permits forward and backward movement of the control stick 75 by the pilot without affecting the ailerons.

Upon lateral motion of the control stick 75 the shaft 72 is caused to rotate and such rotation is transmitted through the gimbal joint 73 to the shaft 68. The shaft 68 rocks and causes arms 67 to move and this movement is transmitted through ball and socket joints to rods 64, through ball and socket joints to crank arms 61. The motion of the crank arms 61 causes the shafts 58 to rotate in opposite directions to raise or lower the ailerons 50 to give desired rolling moments.

It will be apparent from an inspection of the linkages and force transmitting members that the ailerons 50 may seek a position of balance with the forces of the airstream passing over them when not under active control of the pilot through lateral motion of the control stick 75. Let us assume that the plane is flying in such a position that the forces of the airstream tend to raise the trailing edges of the ailerons 50. This will create compression forces in the rods 55 which will cause such rotation of the shafts 58 as to move the rods 64 downwardly. Because of the ball and socket connections of the rods 64 to the cranks 61 and to the arms 67, the effect of the upward motion of the trailing edges of the ailerons 50 is to lower the arms 67 carrying with them the shaft 68. The

motions of the parts freely permit this and the downward movement of the shaft 68, because of the gimbal joint connection at 63, does not in any way interfere with the immovability of the shaft 5 72, nor cause any binding of any of the parts.

On the contrary, upon motion of the control stick 75 in a lateral direction, the ailerons may be differentially operated to give desirable rolling moments.

10 A similar phenomenon occurs when the forces of the airstream passing over the ailerons tend to lower the trailing edge of the ailerons, but in such case the arms 67 are raised, raising with them the end of shaft 68. The link 69, in either direction 15 of movement of the shaft 68, tends to prevent undue lateral movement of the shaft 68 but permits the vertical movement without undue binding or friction.

In Figure 10 I have shown a floating aileron 20 construction in which the floating aileron is pivoted at a point substantially two-thirds of an aileron chord above the upper surface of the wing. This aileron has approximately two-thirds of its chord projecting beyond the trailing edge of the 25 wing.

In Figure 11 I have shown a floating aileron 30 construction in which the leading edge of the aileron lies substantially one aileron chord to the rear of the trailing edge of the wing, and in which the pivot point of the aileron is approximately one half an aileron chord above the upper surface of the wing.

Figure 12 shows another possible location in 35 which the floating aileron is pivoted above the wing at a distance of approximately two aileron chords therefrom, and has approximately half its chord projecting beyond the trailing edge of the wing.

In Figure 13 the floating aileron is pivoted 40 approximately one aileron chord above the upper surface of the wing and has approximately half its chord length projecting behind the trailing edge of the wing.

In Figure 14 I have shown a floating aileron 45 located approximately half an aileron chord above the upper wing surface. Its leading edge is approximately two aileron chords in front of the trailing edge of the wing.

The locations of the floating aileron are 50 supposed to be similar to the locations of the common type of aileron shown and described in connection with Figures 1 to 8, inclusive, and what has been said concerning the locations of the ailerons shown in Figures 1 to 8 inclusive, with 55 respect to their location being substantially within the downflow, is applicable here. The advantages of location, preferable limits of position and other factors are substantially the same for both types of aileron. There are, of course, inherent 60 advantages in floating aileron constructions which are not present in the form shown in Figures 1 to 8 inclusive, and which are present in the form shown in Figures 9 to 14 inclusive.

The floating aileron construction permits the 65 ailerons to seek a position of equilibrium with the forces of the airstream passing over their surfaces which presents certain inherent advantages in acute angles of attack. These advantages are additional to the advantages of the aileron locations which have been previously set forth in some detail.

It is particularly at high angles of attack that 70 the floating aileron is desirable. At high angles of attack ordinary ailerons are in such position 75 as to cause them to be delayed in producing the

desired effect. When the ailerons, however, as in the case of this floating aileron construction, can assume a position of balance with the airstream around them, they are in a position to efficiently operate in response to the pilot's control.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:—

1. An airplane construction comprising an airfoil having a fluid downflow region in flight, an aileron so positioned above and with respect thereto as to have a substantial portion thereof in the downflow over the upper surface of the airfoil to affect the lift of the airfoil over a substantial portion of its surface to increase the lift of the airfoil on lowering the trailing edge of the aileron; or decrease the lift of the airfoil on raising the trailing edge of the aileron.

2. An airplane construction comprising wings having a fluid downflow region in flight, ailerons so positioned above and with respect thereto as to have a substantial portion thereof in the downflow over the upper surface of the wings to increase the downflow of the combination of one wing and its aileron on the side to be raised and to decrease the velocity of the air flow over the upper surface of the opposite side, thereby producing a rotation about the fore and aft axis of the airplane.

3. An airplane construction comprising wings having a fluid downflow region in flight and ailerons so positioned above and with respect thereto as to lie at least partially in the downflow and affect the lift of each wing over a substantial portion of its surface by directly affecting its downflow, each aileron having its leading edge from approximately two aileron chords in front of the trailing edge of a wing to one aileron chord 115 behind the trailing edge of the wing and having its pivot located above the upper wing surface a distance of from approximately one-third of an aileron chord to two aileron chords.

4. An airplane construction comprising wings 125 having a fluid downflow region in flight and ailerons so positioned above and with respect thereto as to lie at least partially in the downflow and affect the lift of each wing over a substantial portion of its surface by directly affecting its 130 downflow, each aileron having its leading edge from approximately two aileron chords in front of the trailing edge of a wing to one aileron chord behind the trailing edge of the wing and located sufficiently close to the upper surface of the wing 135 to affect the flow around the wing.

5. An airplane construction comprising wings having a fluid downflow region in flight and ailerons having a substantial portion of their area in the downflow over the wings and so positioned 140 above and with respect thereto as to affect the lift of each wing over a substantial portion of its surface, each aileron having its pivot located above the upper wing surface a distance of from one-third of an aileron chord to two aileron 145 chords, and having such a fore and aft location as to affect the flow around the wing.

6. An airplane construction comprising wings having a fluid downflow region in flight and ailerons so positioned above and with respect 150

- thereto as to lie at least partially in the downflow and affect the lift of each wing over a substantial portion of its surface, said ailerons being located above the wings and in the vicinity of the rear 5 of the wings and affecting directly the downflow over the wings, the axis of pivoting of said ailerons being substantially perpendicular to the line of flight.
7. An airplane construction comprising wings 10 having a fluid downflow region in flight and ailerons so positioned above and with respect thereto as to affect the lift of each wing over a substantial portion of its surface, each aileron having its leading edge approximately two aileron chords 15 in front of the trailing edge of a wing and having its pivot located above the upper surface of the wing a distance of approximately two aileron chords and directly affecting the downflow over the wings by having at least a portion of its surface 20 in said downflow.
8. An airplane construction comprising wings having a fluid downflow region in flight and ailerons so positioned above and with respect thereto as to affect the lift of each wing over a substantial portion of its surface, each aileron having its leading edge approximately one aileron chord 25 behind the trailing edge of a wing, and having its pivot located above the upper wing surface a distance of approximately two aileron chords; 30 each aileron being at least partially in the downflow.
9. An airplane construction comprising wings having a fluid downflow region in flight and ailerons so positioned above and with respect thereto as to lie at least in part in the downflow and 35 affect the lift of each wing over a substantial portion of its surface, each aileron having its leading edge approximately two aileron chords in front of the trailing edge of a wing and having 40 its pivot located above the upper wing surface a distance of approximately one-third of an aileron chord and directly affecting the downflow over its wing.
10. An airplane construction comprising wings 45 having a fluid downflow region in flight and ailerons so positioned above and with respect thereto as to affect the lift of each wing over a substantial portion of its surface, each aileron having its leading edge approximately two aileron chords 50 in front of the trailing edge of a wing and having its pivot located above the upper wing surface a distance of approximately one aileron chord and having a substantial portion of its area within 55 the downflow over its wing.
11. An airplane construction comprising wings having a fluid downflow region in flight and ailerons so positioned above and with respect thereto as to affect the lift of each wing over a substantial portion of its surface, each aileron having a 60 substantial portion of its surface lying in the downflow over its wing, and having its leading edge approximately two aileron chords in front of the trailing edge of a wing and having its pivot located above the upper wing surface a distance 65 such that the aileron will affect the flow around the wing.
12. An airplane construction comprising wings having a fluid downflow region in flight and ailerons so positioned above and with respect thereto 70 as to affect the lift of each wing over a substantial portion of its surface, each aileron having its pivot substantially directly above the trailing edge of the wing and located approximately half an aileron chord distant therefrom, and each aileron lying substantially in the downflow.
13. An airplane construction comprising wings having a fluid downflow region in flight and ailerons so positioned above and with respect thereto as to affect the lift of each wing over a substantial portion of its surface, each aileron having its pivot substantially directly above the trailing edge of the wing and located approximately an aileron chord distant therefrom, and each aileron lying substantially in the downflow. 80
14. An airplane construction comprising wings having a fluid downflow region in flight and ailerons so positioned above and with respect thereto as to affect the lift of each wing over a substantial portion of its surface, each aileron having its pivot substantially directly above the trailing edge of the wing and located approximately two aileron chords distant therefrom, and each aileron lying substantially in the downflow. 85
15. An airplane construction comprising wings having a fluid downflow region in flight and ailerons so positioned above and with respect thereto as to affect the lift of each wing over a substantial portion of its surface, each aileron having its leading edge approximately one aileron chord in front of the trailing edge of a wing and having its pivot located above the upper wing surface approximately an aileron chord distant therefrom, and each aileron lying substantially in the downflow. 90
16. An airplane construction comprising wings having a fluid downflow region in flight and ailerons so positioned above and with respect thereto as to affect the lift of each wing over a substantial portion of its surface, each aileron having its leading edge substantially directly above the trailing edge of a wing and having its pivot located approximately half an aileron chord above the upper wing surface at its trailing edge, and having at least a portion of its surface in the downflow. 105
17. An airplane construction comprising wings having a fluid downflow region in flight and ailerons so positioned above and with respect thereto as to affect the lift of each wing over a substantial portion of its surface, each aileron having its leading edge substantially directly above the trailing edge of a wing and having its pivot located at approximately one aileron chord above the upper wing surface at its trailing edge, and having at least a portion of its surface in the downflow. 110
18. An airplane construction comprising wings having a fluid downflow region in flight and ailerons so positioned above and with respect thereto as to affect the lift of each wing over a substantial portion of its surface, each aileron having its leading edge substantially directly above the trailing edge of a wing and having its pivot located at approximately two aileron chords distant from the upper wing surface at the trailing edge, and having at least a portion of its surface in the downflow. 115
19. An airplane construction comprising wings having a fluid downflow region in flight and ailerons so positioned above and with respect thereto as to affect the lift of each wing over a substantial portion of its surface, each aileron having its trailing edge substantially in line with the trailing edge of the wing and having its pivot located above the upper wing surface approximately half an aileron chord distant therefrom, and having at least a portion of its surface in the downflow. 120
20. An airplane construction comprising wings having a fluid downflow region in flight and 125

- ailerons so positioned above and with respect thereto as to affect the lift of each wing over a substantial portion of its surface, each aileron having its trailing edge substantially in line with the trailing edge of the wing and having its pivot located above the upper wing surface approximately one aileron chord distant therefrom, and having at least a portion of its surface in the downflow. 80
- 10 21. An airplane construction comprising wings having a fluid downflow region in flight and ailerons so positioned above and with respect thereto as to affect the lift of each wing over a substantial portion of its surface, each aileron having its trailing edge substantially in line with the trailing edge of the wing and having its pivot located above the upper wing surface approximately two aileron chords distant therefrom, and having at least a portion of its surface in the downflow. 85
- 15 22. An airplane construction comprising wings having a fluid downflow region in flight and ailerons so positioned above and with respect thereto as to affect the lift of each wing over a substantial portion of its surface, each aileron having its trailing edge substantially in line with the trailing edge of the wing and having its pivot located above the upper wing surface at such a distance that the flow around the wing is materially affected both positively and negatively by angular movement of the aileron, and having at least a portion of its surface in the downflow. 90
- 20 23. An airplane construction comprising wings having a fluid downflow region in flight and separate detached ailerons located substantially in the downflow over the wings and so related to the wings as to affect the flow over a sufficient area of the wings that there is produced a usable and practical rolling moment in addition to the rolling moment produced by the airfoil sections of the ailerons. 95
- 25 24. A floating aileron construction comprising an airfoil having a fluid downflow region in flight, a floating aileron so positioned above and with respect thereto as to affect the flow around the airfoil to give both positive and negative lift effect on said airfoil, depending upon angular movement of the aileron, said aileron being located substantially in the downflow over the airfoil. 100
- 30 25. A floating aileron construction comprising wings having a fluid downflow region in flight, and floating separate detached ailerons so related to the wings as to affect the flow over a sufficient area of the wings that there is produced a usable and practical rolling moment in addition to the rolling moment produced by the airfoil sections of the ailerons themselves, said ailerons having a substantial portion of their area in the downflow over the wings. 105
- 35 26. A floating aileron construction comprising wings having a fluid downflow region in flight, and separate detached ailerons so positioned above and with respect thereto as to affect the lift of each wing over a substantial portion of its surface, each floating aileron lying within the downflow over its wing and having its leading edge from approximately two aileron chords in front of the trailing edge of the wing to one aileron chord behind the trailing edge of the wing and located sufficiently close to the upper surface of the wing to affect the flow around the wing. 110
- 40 27. A floating aileron construction comprising wings having a fluid downflow region in flight, and floating ailerons so positioned above and with respect thereto as to affect the lift of each wing over a substantial portion of its surface, each aileron having its leading edge from approximately two aileron chords in front of the trailing edge of a wing to one aileron chord behind the trailing edge of the wing and having its pivot located above the upper wing surface a distance of from approximately one-third of an aileron chord to two aileron chords, and lying in the downflow. 115
- 45 28. A floating aileron construction comprising wings having a fluid downflow region in flight, and floating ailerons so positioned above and with respect thereto as to affect the lift of each wing over a substantial portion of its surface, said ailerons being located above the wings and in the vicinity of the rear of the wings, and lying substantially in the downflow. 120
- 50 29. In the combination of an airfoil, having a fluid downflow region in flight, and aileron, an aileron of the relatively log narrow type so positioned as to be in and directly influence the downflow over a relatively large area of the airfoil, and control means for the aileron adapted to give a lesser motion to the trailing edge of the aileron in the down direction for a given initial movement by the pilot than in the upward direction, whereby the lift of the airfoil is largely affected by movement of the aileron to give practical and usable rolling moments due to change in the lift of the airfoil itself, as distinguished from the rolling moment produced by the airfoil section of the aileron. 125
- 55 30. In the combination of an airfoil, having a fluid downflow region in flight, and aileron, a floating aileron of the relatively long narrow type so positioned as to be in and directly influence the downflow over a relatively large area of the airfoil and adapted to seek a position of balance with the forces of the airstream passing its surface, and control means for the aileron adapted to give a lesser motion to the trailing edge of the aileron in the down direction for a given initial movement by the pilot than in the upward direction, whereby the lift of the airfoil is largely affected by movement of the aileron to give practical and usable rolling moments due to change in the lift of the airfoil itself, as distinguished from the rolling moment produced by the airfoil section of the aileron. 130
- 60 31. In an airplane, wings having a fluid downflow region in flight, an aileron for each wing located above the wing and having a substantial portion of its area located in the downflow over its wing, means to operate the ailerons to lower the trailing edge of one while the trailing edge of the other aileron is raised, the trailing edge of the raised aileron having a greater motion than the trailing edge of the lower aileron where- 135
- 65 32. In an airplane, wings having a fluid downflow region in flight, an aileron for each wing located above the wing and having a substantial portion of its area located in the downflow over its wing, means to increase in the lift of the wing on which the trailing edge of the aileron is lowered, which are additive to the rolling moments produced by the airfoil section of the aileron itself 140
- 70 33. In an airplane, wings having a fluid downflow region in flight, an aileron for each wing located above the wing and having a substantial portion of its area located in the downflow over its wing, means to increase in the lift of the wing carrying the aileron whose trailing edge is raised is lowered over its normal performance to such an extent as to create practical and usable rolling moments tending to lower that wing because of its loss in lift, which rolling moments are in addition to the rolling moments tending to lower the wing which arise from the airfoil section of the aileron located on that wing. 145
- 75 34. In an airplane, wings, having a fluid down- 150

flow region in flight, a floating aileron for each wing located above the wing and having a substantial portion of its area located in the downflow over its wing adapted to seek a position of balance with the forces of the airstream passing its surface, means to operate the floating ailerons to lower the trailing edge of one while the trailing edge of the other is raised, the trailing edge of the raised aileron having a greater motion than the trailing edge of the lowered aileron whereby practical and usable rolling moments are generated by increase in the lift of the wing on which the trailing edge of the aileron is lowered, which are additive to the rolling moments produced by the airfoil section of the aileron itself on that wing, and the lift of the wing carrying the aileron whose trailing edge is raised is lowered over its normal performance to such an extent as to create practical and usable rolling moments tending to lower that wing because of its loss in lift, which rolling moments are in addition to the rolling moments tending to lower the wing which arise from the airfoil section of the aileron located on that wing.

33. In an aircraft, an airfoil having a trailing edge and having a fluid downflow region in flight, an aileron carried by said aircraft and positioned spaced above and substantially rearwardly of the trailing edge of said airfoil and substantially in the downflow; and means to control said aileron.

34. An airplane construction comprising an airfoil having a fluid downflow region in flight, an aileron so positioned above and with respect thereto as to have a substantial portion of its

area in the downflow to affect the flow around the airfoil to give both positive and negative lift effect on said airfoil, depending respectively upon down and up movement of the aileron.

35. An airplane construction comprising wings having a fluid downflow region in flight, ailerons so positioned above and with respect thereto as to have a substantial portion of its area in the downflow to increase the downflow of the wing to be raised by lowering the trailing edge of an aileron and to decrease the velocity of the airflow over the upper surface of the wing to be lowered by raising the trailing edge of an aileron, thereby producing a rotation about the fore and aft axis of the airplane.

36. An airplane construction comprising airfoils having fluid downflow regions in flight, floating ailerons adapted to float together and so positioned above and with respect to the airfoils as to have a substantial portion of their area in the downflow to affect the flow around each airfoil to give both positive and negative lift effect on said airfoil, depending upon up and down movements of the ailerons.

37. A floating aileron construction comprising wings having a fluid downflow region in flight, ailerons adapted to float together and so positioned above and with respect to the wings as to affect the lift of each wing over a substantial portion of its surface, said ailerons being located above the wings and in the vicinity of the rear of the wings and lying substantially in the downflow.
